UNITED STATES PATENT OFFICE.

MORRIS OZLEK, OF PHILADELPHIA, PENNSYLVANIA.

CLUSTER-TOP FOR LAMPS.

1,355,164.

Specification of Letters Patent.

Patented Oct. 12, 1920.

Application filed February 26, 1920. Serial No. 361,593.

To all whom it may concern:

Be it known that I, MORRIS OZLEK, a citizen of the United States, residing at Philadelphia, in the county of Philadelphia and State of Pennsylvania, have invented 5 certain new and useful Improvements in Cluster-Tops for Lamps, of which the following is a specification.

It has long been a source of trouble and 10 inconvenience to attach a number of electric lamp sockets to the tops of standards of floor and table lamps especially where the lamp stands and tops are made of wood. Various types of tops have been made, cer- 15 tain of which required the making of individual sections which were screwed together in order to provide a chamber into which the electric conduit wires from the sockets could be manipulated and joined 20 or spliced.

One object of my present invention is to provide an improved cluster top for electric lamps which will facilitate the connection of the conduit wires and lamp sockets 25 thereto.

Another object is to so construct my im- 30 proved cluster top that it can be quickly made at a low cost and so that the same knob which is used to secure the shade to the stand will also serve to secure the sections together without the inclusion of any independent screws for said latter purpose.

These objects, and other advantageous ends which will be described hereinafter, I 35 attain in the following manner, reference being had to the accompanying drawings in which

Figure 1 is a sectional elevation of my improved cluster top showing the same in 40 operative position with electric sockets connected thereto and illustrating the arrangement of the wiring.

Fig. 2 is a sectional elevation drawn on a smaller scale than Fig. 1 showing the main 45 section of my improved cluster top and illustrating how the structure thereof facilitates the initial insertion of the electric conduit wires into the top so that the sockets can be easily attached to the top by 50 their screw threaded nipples,

Fig. 3 is a view of similar character to Fig. 2 showing the same after the sockets have been attached to the top and the ends of the conduit wires have been bent and

again inserted into the top so as to pass 55 downwardly through the hole in the standard thereof.

Fig. 4 is a top plan view of the main sec- 60 tion of my improved cluster top and drawn on the scale of Fig. 1,

Fig. 5 is a top plan view of a covering ring which forms a part of my invention,

Fig. 6 is an elevation of the ring shown in Fig. 5,

Fig. 7 is an elevation of a securing knob 65 which forms a part of my invention and which serves to hold the covering ring in place and also to secure a shade to the top, and

Fig. 8 is a top plan view of Fig. 7. 70

Referring to the drawings my improved cluster top includes a main section 9 which is preferably made of wood and turned on a lathe so as to produce an upwardly flaring head 10 at its upper end. In the present in- 75 stance the main section 9 is made of a com- paratively great length to provide a stand- ard 11 at its bottom which can be attached to any form of base either for a table or floor lamp.

In making the main section 9, an integral tenon 12 is turned preferably in a cylindrical form as illustrated so as to project upwardly from the surface 13 which repre- 85 sents the top of the tapered head 10. A hole or central channel 14 is drilled centrally through the main section 9 from the bottom 15 into the flared head 10. This channel 14 however stops short of the top of the head 10, and two holes 16 and 17 are drilled down- 90 wardly through the head 10 at converging angles. In drilling these holes 16 and 17 a part of the tenon 12 is drilled or cut away at portions which are preferably diametri- 95 cally opposite so as to provide slanting sur- faces 18 and 19 which are continuous from the tenon 12 into the head 10. The holes 16 and 17 intersect or join each other within the head so as to provide a communicating chamber 20 and the channel 14 leads up- 100 wardly and communicates with the chamber 20 and the holes 16 and 17. A screw 21 is inserted into the top of the tenon 12 and a portion 22 of this screw 21 projects above the tenon 12 and is adapted to receive a 105 knob 23 which has a screw threaded hole 24 into which the portion 22 of the screw 21 fits. The bottom portion of the knob 23 is

made of larger diameter than the top of the tenon 12.

A covering ring 25 has a hole 26 adapted to slidably fit the tenon 12; said covering ring at its base 27 being of such diameter as to completely cover the holes 16 and 17 and rest upon the top surface 13 as clearly shown in Fig. 1. The ring 25 is preferably made of the same height as the tenon 12 so that its uppermost portion is flush with the top of the tenon 12 and so that when the knob 23 is screwed in place upon the screw 21 that said knob will normally serve to lock the ring 25 in said position covering the holes 16 and 17. The outer surface of the ring 25 is preferably curved or otherwise shaped to present an ornamental configuration and so as to co-act ornamentally with the shape of the flared head 10 to produce a pleasing design or shape for the cluster top. The flared head 10 has apertures 28 and 29 drilled in its sides; said apertures extending upwardly at converging angles to provide connection for screw threaded nipples 30 for attachment to the electric lamp sockets 31.

The construction and arrangement of the parts of my improved top facilitates the attachment of the lamp sockets 31 and the electric conduit wires 32. It will be noted that the apertures 28 and 29 are so positioned that they extend in a direction toward the respective slanting surfaces 18 and 19. By thus arranging the parts, when it is desired to attach the sockets and electric wires to the top, it is merely necessary to insert the ends of the wires, which are respectively attached to the sockets, through the apertures 28 and 29 and said ends as shown at the right hand side of Fig. 2 will initially engage the slanting surface 19 and will be deflected upwardly out of the hole 17 where they can be easily grasped by the hand and the wires can be pulled upwardly until the socket and nipple are in line with the aperture and the socket can be easily attached to the head 10. Fig. 2 at the left hand side shows how the wires can be pulled upwardly through one of the holes, in the present instance the hole 16, after which the socket and nipple can be attached with the nipple 30 within the aperture 28. After the sockets have been attached as shown in Fig. 3, the wires can then be bent and the free ends can be projected downwardly through the holes 16 and 17 and here again the slanting surfaces 18 and 19 will serve as deflecting means for directing the ends of the wires downwardly through the channel 14 and outwardly through the bottom thereof, as shown in Fig. 1, after which they can be spliced or coupled to the feed wires.

If desired the coupling nipples 30 can be screwed in the apertures 29 before the wires are inserted and the wires can be inserted

through the nipples and will act in the same manner as above described. In this instance the sockets can be secured to the nipples in the usual manner.

It will be noted that a shade, which is usually provided with a spider having a central hole therein, can be attached to my improved cluster top between the knob 23 and the top of the tenon 12 and the knob 23 will then serve to hold the shade in position and will also prevent the shade or the covering ring 25 from moving upwardly out of position. It will be further noted that the holes 16 and 17 and chamber 20 are properly covered by the ring 25 without requiring that any independent screws or other securing means be employed to hold the ring 25 in position.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A cluster top of the character described including a main section having a head provided with an upwardly extended tenon, said head having holes drilled downwardly therethrough at converging angles whereby upwardly slanting surfaces are provided, said head having apertures communicating with said holes whereby electric conduit wires can be inserted through said apertures so as to engage said slanting surfaces to deflect the wires upwardly and out of said holes, said section including a channel leading downwardly from said holes whereby said wires can be projected downwardly through said channel; a ring fitting said tenon and covering said holes; and means for securing said ring in position; substantially as described.

2. A cluster top of the character described including a main section having a head provided with an upwardly extending tenon, said head having holes drilled downwardly therethrough at converging angles whereby upwardly slanting surfaces are provided, said head having apertures communicating with said holes whereby electric conduit wires can be inserted through said apertures so as to engage said slanting surfaces to deflect the wires upwardly and out of said holes, said section including a channel leading downwardly from said holes whereby said wires can be projected downwardly through said channel; a ring fitting said tenon and covering said holes; a screw projecting upwardly from said tenon; and a

knob fitting said screw and adapted to hold said ring in position; substantially as described.

3. A cluster top of the character described including a main section having a head provided with an upwardly extending tenon, said head having holes, said holes extending downwardly from its top and a hole extending upwardly from its bottom and communicating with said first holes, said head having apertures communicating with said first holes; a ring fitting said tenon and adapted to cover the tops of said holes; and means for securing said ring in position; substantially as described.

4. A cluster top of the character described including a main section having a head provided with an upwardly extending tenon,

said head having holes, said holes extending downwardly from its top and a hole extending upwardly from its bottom and communicating with said first holes, said head having apertures communicating with said first holes; a ring fitting said tenon and adapted to cover the tops of said holes; a screw projecting upwardly from said tenon; and a knob fitting said screw and adapted to hold said ring in position; substantially as described.

In testimony whereof I have signed my name to this specification in the presence of two subscribing witnesses.

MORRIS OZLEK.
